UNITED STATES PATENT OFFICE.

ALOYSIUS C. LIPPERT, OF KENOSHA, WISCONSIN, ASSIGNOR OF ONE-HALF TO C. A. NORTON, OF CHICAGO, ILLINOIS.

RADIATOR-LOCKING CAP.

Application filed January 24, 1923. Serial No. 614,520.

My invention has general reference to radiator caps for automobiles, or the like, and relates more particularly to the provision of improved and simplified means for preventing theft of the cap and the motometer which is normally secured thereto.

While the general purpose of the device is similar to that shown in a pending application of William V. Lippert, bearing Serial No. 540,990, the present invention contemplates the provision of an inexpensive and yet efficient construction adapted especially for use upon automobiles of small and relatively cheap make.

The invention also contemplates a construction in which separate collar members are provided, one of which is threaded, or otherwise secured to the radiator neck, and the other locked thereto in such manner as to prevent separation or removal of said first-mentioned collar.

An important object is the provision of combined locking and ratchet means arranged between said separate collars and serving to prevent separation thereof while permitting positioning of the device upon the radiator after assembly. In this connection, it is to be noted that provision is made for turning the outer collar with respect to the inner after said collars are locked together, in order to prevent the unscrewing of the device from the radiator neck and that the ratchet construction referred to, while permitting this action, causes the collars to be turned together in one direction, whereby the assembled device may be positioned upon the car.

A further object of the invention is the provision of improved means for securing a pivoted cover, which is provided on the outer collar, in closed position and in steam-tight relationship to the inner collar.

Other objects and advantages of the invention will be apparent as it is better understood from the following description, which, taken in connection with the accompanying drawings, discloses a preferred embodiment thereof.

Referring to the drawings:

Figure 1 is a front elevation, partially in section, of a radiator cap in which my invention is embodied, the same being shown in position upon an automobile radiator;

Fig. 2 is a sectional view taken substantially on the line 2-2 in Fig. 1; 55

Fig. 3 is an elevational view, partially sectionalized, of an internal collar employed in the device;

Fig. 4 is a horizontal section of said collar taken substantially on the line 4-4 in 60 Fig. 3; and

Fig. 5 is a detail view showing the ratchet recess in the external collar.

Fig. 6 is a side elevation of a radiator cap embodying my invention having parts thereof broken away and showing the cover hinge and latching ridges. 65

For purposes of illustration, I have shown on the drawings a part of an automobile radiator 11 having a short, internally-threaded 70 neck 12 in which is secured a radiator cap, generally indicated by the reference character 13, said cap having a motometer, or temperature indicator, 14 permanently secured thereto. 75

The radiator cap 13 comprises an external collar 15 having arms 16 extending laterally therefrom and being preferably provided with end parts 17 of pleasing ornamental appearance. A cover 18 is suitably hinged to the external collar 15 and the motometer 14 is permanently secured to said cover having a stem extending therethrough and into an opening leading into the radiator. A projection 19 is provided at the front of the 85 cap and may bear a suitable insignia, or pleasing design.

As a means of holding the cover, or closure 18 in closed position, I provide a wire latch 21 pivoted to the sides of the projection 19 and adapted to engage over ridges 22 provided at the front of the cover, a suitable finger hold 23 being provided for the operation of this latch. 90

Inasmuch as the motometer 14 and the ornamental cap by which it is carried are of considerable value, it is very desirable to provide means for preventing the theft of said parts and for this purpose, I provide a locking device to be now described. 95

An internal collar 24 is provided having screw threads 25 adapted to engage the internal threads of the neck 12. The external collar 15 is locked to the collar 24 by means of resilient projections, or lips, 26 which, in the present instance, are secured by rivets 100 105

27 to the collar 24, the point of attachment being in depressions, or counter-sinks 28 provided in the base of the collar. The projections 26 are curved outwardly so that 5 the lower ends thereof normally project from the surface plane of the collar 24 but may be forced into the depressions 28. It will be manifest that this permits the telescopic assembly of the collars and that the 10 lips 26 may expand into a groove, or recess, 29 which is provided on the inner face of the collar 15. Said recess is formed with a suitable ledge, or shoulder, 31 at the bottom adapted to retain the lips 26 to prevent separation of the collars after assembly. There 15 are, in the present instance, a plurality of the parts 26 and it will be understood that these may be provided in any suitable number and arrangement. While this construction 20 prevents the removal of the outer collar from the inner, it permits rotation of said outer collar with respect to the inner so that it will be impossible to unscrew the inner collar from the radiator neck by turning 25 said outer collar.

While it is essential for the purpose just stated that the collar 15 shall have relative rotary movement with respect to the collar 24 in one direction, in order to prevent unscrewing of said collar 24 from the radiator neck, it is desirable that the collars turn together in the other direction, in order to 30 permit positioning of the cap after assembly of the parts. I, therefore, provide a 35 ratchet, consisting of a lateral projection 32, preferably integral with one of the members 26, the depression 28 associated with this particular member being elongated at 33 to permit the projection 32 to be disposed beneath the surface of the collar during rotation of the outer member. A recess 34 is provided at the top of the recess 29 and is adapted to receive the projection 32 when the outer collar is turned in the direction necessary for screwing the collar 24 into 40 the radiator neck. When turned in the opposite direction, however, the projection 32 is forced into the depression 33 and the outer collar may be freely rotated without effect 45 upon said inner collar.

The collar 24 is provided at the top with 50 a shoulder 35 having an upstanding flange 36 about a central opening 37. A gasket 38, of rubber, or other suitable material, is adapted to be arranged upon the shoulder 35 and beneath an inward extension 39 at the top of the collar 15. The cover 18 is adapted to rest upon the part 39 of the collar 15 and is provided with a downwardly 55 extending part 41 adapted to fit within the extension 39 and rest upon the gasket 38. By means of the closing device heretofore described, this cover may be brought tightly 60 down upon said gasket to prevent escape of steam except through the motometer stem.

It will be observed that by this construction a very small portion of the gasket 38 is exposed to the passageway for the steam and said gasket is thus protected against deterioration which might result from having 70 the greater part subjected to heat and moisture.

It is thought that the invention and many of its attendant advantages will be understood from the foregoing description, and it 75 will be apparent that various changes may be made in the form, construction and arrangement of the parts without departing from the spirit and scope of the invention, or sacrificing all of its material advantages, 80 the form hereinbefore described being merely a preferred embodiment thereof.

I claim:

1. A radiator cap comprising, in combination, an outer collar forming the body of 85 the cap, a hinged cover for the top of said collar, an inner collar forming a concealed attaching member adapted to be applied to the radiator opening, and means for connecting said collars together in such manner as to prevent theft of the outer collar and to cause said collars to turn together when the outer collar is rotated in one direction but not when rotated in the other, said means comprising a unitary connecting member secured to said inner collar beneath the circumferential surface thereof and having resilient portions arranged at right angles to each other and projecting from the surface of said inner collar, the outer collar being provided with shoulders 90 extending respectively in horizontal and vertical direction and adapted to be engaged by said projecting portions of said connecting member to both lock the inner and outer collars against relative axial movement after assembly and to cause said collars to turn together when the outer collar is turned in one direction while permitting the outer collar to ride free over the inner collar when rotated in the opposite direction.

2. A radiator cap comprising, in combination, an outer collar forming the body of 100 the cap, a hinged cover for the top of said collar, an inner collar forming a concealed attaching member adapted to be applied to the radiator opening, and means for connecting said collars together in such manner as to prevent theft of the outer collar and to cause said collars to turn together when the outer collar is rotated in one direction but not when rotated in the other, said means comprising a plurality of unitary connecting members spaced circumferentially of 105 said inner collar and each secured thereto beneath the circumferential surface thereof, one of said members having resilient portions arranged at right angles to each other and projecting from the surface of said in- 110

ner collar, the outer collar being provided with shoulders extending respectively in horizontal and vertical direction and adapted to be engaged by said projecting portions 5 of said connecting member to both lock the inner and outer collars against relative axial movement after assembly and to cause said collars to burn together when the outer collar is turned in one direction while permitting the outer collar to ride free over the inner collar when rotated in the opposite direction.

3. A radiator cap comprising, in combination, an outer collar forming the body of the 15 cap, a hinged cover for the top of said collar, an inner collar forming a concealed attaching member adapted to be applied to the radiator opening, and means for connecting said collars together in such manner as to 20 prevent theft of the outer collar and to cause said collars to turn together when the outer collar is rotated in one direction but not when rotated in the other, said means comprising a plurality of unitary connecting 25 members spaced circumferentially of said inner collar and each secured thereto beneath the circumferential surface thereof, one of said members having resilient portions arranged at right angles to each other and 30 projecting from the surface of said inner collar, the outer collar being provided with shoulders extending respectively in horizontal and vertical direction and adapted to be engaged by said projecting portions of said 35 connecting member to both lock the inner and outer collars against relative axial movement after assembly and to cause said collars to turn together when the outer collar is turned in one direction while permitting the outer collar to ride free over the inner collar when rotated in the opposite 40 direction, said inner collar being formed of sheet brass, or like workable material, and

being pressed inwardly at appropriate points to provide recesses for the reception 45 of said connecting members.

4. A radiator cap comprising, in combination, an outer collar forming the body of the cap, a hinged cover for the top of said collar, an inner collar forming a concealed 50 attaching member adapted to be applied to the radiator opening, and means for connecting said collars together in such manner as to prevent theft of the outer collar and to cause said collars to turn together when the 55 outer collar is rotated in one direction but not when rotated in the other, said means comprising an L-shaped spring member secured to said inner collar with the ends thereof projecting outwardly from the surface of the collar and said outer collar being provided with shoulders adapted to cooperate with said projecting portions of said L-shaped member to connect said collars in the 60 manner aforesaid.

5. A radiator cap comprising, in combination, an outer collar forming the body of the cap, a hinged cover for the top of said collar, an inner collar forming a concealed 65 attaching member adapted to be applied to the radiator opening, and means for connecting said collars together in such manner as to prevent theft of the outer collar and to cause said collars to turn together when the outer collar is rotated in one direction but not when rotated in the other, said means comprising a plurality of spring members secured to said inner collar with the ends thereof projecting outwardly from the surface of the collar, one of said members being L-shaped and said outer collar being provided with shoulders adapted to cooperate with said projecting portions of said L-shaped member to connect said collars in the 70 manner aforesaid.

ALOYSIUS C. LIPPERT.
